UNITED STATES PATENT OFFICE.

ARTHUR BATES, OF LEICESTER, ENGLAND, ASSIGNOR, BY MESNE ASSIGNMENTS, TO
UNITED SHOE MACHINERY CORPORATION, OF PATERSON, NEW JERSEY, A COR-
PORATION OF NEW JERSEY.

UPPER-SHAPING MACHINE.

1,419,204.

Specification of Letters Patent. Patented June 13, 1922.

Application filed June 15, 1916. Serial No. 103,747.

To all whom it may concern:

Be it known that I, ARTHUR BATES, a subject of the King of England, residing at Leicester, Leicestershire, England, have invented certain Improvements in Upper-Shaping Machines, of which the following description, in connection with the accompanying drawings, is a specification, like reference characters on the drawings indicating like parts in the several figures.

This invention relates to machines for use in the manufacture of boots and shoes for shaping the upper materials over a last or other shoe form, and is herein illustrated in its application to a well-known type of pulling-over machine, the machine herein shown including means for pulling over the upper and means for wiping the toe end portion of the upper into lasted relation to a sole or insole, herein frequently termed for convenience the "sole". It is to be understood, however, that in various novel aspects the invention is not limited to a machine of the particular type illustrated nor to a machine including both pulling over means and lasting means. It will also be recognized that in some of its novel aspects the invention is not confined, in respect to the shaping of the upper materials over a form, to what is generally understood as lasting in the restricted sense.

In the shaping of the toe end portion of welt shoe upper materials in the characteristic contour to lie inwardly over the feather of the sole and to conform to the angle between the feather and the rib of the sole, particular difficulties are encountered in gathering and wiping the materials inwardly over the bottom of the form in such manner as to avoid the presence of wrinkles in portions of the upper which are visible in the finished shoe, due to the gathering of the marginal portion of the upper within a contracted area inwardly from the edge of the form. The present invention provides, as an important feature, novel means for working the margin of the upper of a welt or other type of shoe inwardly over the bottom of a form under such control as to shape the upper smoothly and free from wrinkles along the edge of the form. For the purposes in view, the construction shown comprises a flexible loop wiper and means for operating it to gather the upper materials

about the toe and to wipe them inwardly over the bottom of the form, together with means for controlling the margin of the upper in such manner as to hold it smooth and free from wrinkles and to render the wiper effective to draw and wipe the upper inwardly with the required pressure. In the illustrative machine the control of the margin of the upper is effected by clamping means which permits the upper to slip in response to the pull of the flexible wiper in order to equalize the tension under which the upper is shaped at the different points about the toe, a portion of the clamping means being also movable inwardly over the bottom of the form to assist in the over-wiping operation and in maintaining the flexible wiper close to the plane of the shoe bottom.

A further feature of the invention consists in a novel organization of upper pulling means and means for working the margin of the upper inwardly about or over a form, the construction shown comprising marginal clamping means as hereinabove set forth which is operative by relative movement between it and the form to pull the upper over the form under such control as to permit the margin to slip in response to excessive tension in the upper pulling operation as well as in the subsequent overwiping operation of the flexible wiper. Included also in the organization herein shown are side grippers which in addition to pulling the upper over the top of the form have an overdrawing movement to carry the margin inwardly over the bottom of the form in time relation to other operations of the machine. An important feature is also to be recognized in a novel organization including means for controlling the pressure on the clamped margin of an upper in such manner as to reduce the pressure for the operation of working the upper inwardly about or over the form. In the construction shown, wherein the margin of the upper is permitted to slip in response to excess of tension in both the upper pulling operation and the overworking operation, the clamping means is so controlled as to relax the clamping pressure automatically after the upper pulling operation to permit the upper to slip more freely as it is wiped inwardly over the bottom of the form while still under effective control of the clamping means.

A further feature of the invention consists in a novel organization including upper fastening means, the construction shown comprising means for applying and fastening a binder about the toe while the margin of the upper is held in position by the flexible wiper. The illustrative machine is so controlled in its cycle of operations as to come automatically to a stop after the upper 10 has been pulled and before it is wiped inwardly, to permit any adjustment of the upper which may be required, and to come again to a stop with the upper held by the wiper to permit a binder to be drawn manually about the toe, the machine operating when again started to tighten the binder and to fasten it at the opposite sides of the shoe.

Still other features of the invention are to be recognized in novel means for effecting 20 the clamping and the pulling of the upper, in novel details of the clamping means, and in various other details of construction and combinations of parts, which will now be more particularly described in connection 25 with the accompanying drawings and pointed out in the claims.

Fig. 1 of the drawings is a side elevation of a portion of a pulling-over machine with this invention incorporated in it.

30 Fig. 2 is a front elevation of so much of the machine shown in Fig. 1 as includes the holding means for the toe of the upper.

Fig. 3 is a front elevation of details of the novel lasting mechanism to be described.

35 Figs. 4 to 7 inclusive are details of a toe binder applying mechanism.

The frame of the machine constituting the illustrated embodiment of this invention and the various mechanisms which co-operate in 40 pulling-over a shoe may be, except as herein particularly pointed out, like those fully shown and described in prior United States Letters Patent No. 1,135,949, of April 13, 1915, the same being well known in the practical art and needing no detailed illustration or description for the purposes of this specification. It will suffice to state that the machine comprises a sole rest 1 against which the tread face of the shoe is positioned for 50 side grippers 2 to engage the upper at opposite sides of the ball of the last. The sole rest is operated by a cam 4 on the cam shaft 5 to force the last downwardly relatively to the grippers in pulling the upper. The grippers are connected by updraw levers 6 and springs 7 with a slide 8 that receives motion from a cam on the cam shaft, and are moved outward to outdraw the upper by a slide 124 which receives motion from the cam 55 shaft, and are reversely moved by springs 7^x to overdraw the upper when the slide 124 is retracted. A heel rest is also provided which comes into position after the upper is pulled to hold the shoe against backward 60 placement in the toe shaping and fastening

operations. The mechanism comes to rest automatically for inspection of the pulled upper and is thereafter restarted, whereupon side clamps 9 seize the shoe and uphold it while fastening tacks are inserted from tackers 10 to hold the upper in pulled-over position at the sides of the last.

The yieldingly pulling toe gripper of the machine illustrated in the patent above mentioned is herein replaced by toe holding 75 means of novel construction and having a novel manner of operation. The front bracket 15 of the machine frame is reconstructed to provide a stationary support having bearings for a sliding plate 16 that is 80 movable in a plane parallel with the plane in which the sole rest 1 holds the shoe bottom when the sole rest occupies its final position at the end of the upper pulling operation.

The sliding plate 16 has in its face or edge 85 that is toward the sole rest a recess, Fig. 2, that more or less fits the toe of the shoe so that the lateral sides of the plate extend around the corners of the toe when the plate is in proximity to the end of the toe. The 90 plate 16 will normally stand in its rearmost position, that is, its position nearest to the heel end of the shoe. The plate is capable of being moved in its guideway in the guide or support 15 by a connection 17, from which it is readily detachable to facilitate changing one plate for another of different shape, with a link 18, bell-crank 19, link 20, lever 21 and rod 22 to a foot treadle, not shown, that is yieldingly upheld by a spring (not shown) 100 against an adjustable stop that determines the normal position of the plate longitudinally of the machine.

For co-operation with the plate 16 to hold the toe of the upper there is guided for up and 105 down movement in the bracket 15 a clamping member 25 the foot of which is shaped at its edge toward the sole rest similarly to the corresponding edge of the plate 16. The stem of clamp 25 comprises opposite side 110 plates slidable in guideways in the bracket, the connection being loose enough to allow the foot to tip to adapt itself automatically to differences in thickness of clamped stock at different points. Between said plates is pivoted a connecting member 23 which is perforated transversely to receive the reduced lower end of a rod 24 depending from one arm of a bell-crank 28 which is pivoted at 29 on an angle lever 30. A nut on the rod 24 115 engaging the lower surface of the member 23 serves to raise the clamp member when the rod is moved upwardly. The angle lever 30 is suspended from the front arm 32 of a bell-crank 35 fulcrumed in the machine head at 125 34 and having a rear arm connected by link 36 with a lever 40 which corresponds to the toe gripper updraw lever of the patented machine. The lever 40 is unyieldingly connected at its rear end by a link 38 to a cam 130

slide operated positively from a track cam on the cam shaft. Through these connections the clamping member 25 is raised and lowered. The downward or upper clamping movement is rendered yielding by a spring 45 that encircles the rod 24 between a shoulder on the upper end of the rod and a washer engaging the member 23 and is compressed to a substantial extent by the cam motion as 10 the rod slides downwardly through the member 23. This arrangement has two purposes. It accommodates varying thicknesses of upper materials automatically and it provides for a partial relief of the clamping pressure 15 to allow the upper to be drawn out of the clamp under tension.

It will be understood that in the use of the machine a shoe is presented with its tread face against the sole rest, the sides of the 20 upper being arranged within the jaws of the grippers and the toe of the upper spread over plate 16 in position to be clamped by the foot of member 25. Before the shoe is thus presented the plate 16 is moved forwardly 25 by its treadle to make room for the shoe, the treadle being then released to permit its spring to move the plate rearwardly as far as permitted by the end face of the last. When power is applied to the cam shaft the 30 clamping member 25 is depressed to clamp the toe of the upper yieldingly under the compression of spring 45, and the side grippers are closed and then updrawn, while at the same time the sole rest is rocked by 35 its cam 4 to force the last downwardly and thereby to stretch the upper between the last on the one hand and the grippers and clamp on the other hand, and then the machine comes to rest. This organization introduces 40 the new feature in a machine of the illustrated type that the toe of the upper is clamped on a continuous line all the way around the toe and then the last is depressed into the upper and when the high points of 45 the toe of the last produce excessive tension on the upper at certain places the clamp allows the upper to slip to give up stock at those places. The result is that the top of the toe of the last is covered with upper 50 stock that is under uniform strong tension at all points. The upper is not tensioned materially more over the high points which give the character to the style of the toe than it is tensioned over the low places. This 55 produces a toe that stands up in its original shape when the last is withdrawn from the shoe, and eliminates the loss of shape that is due to unequal strains.

The cycle of the machine is divided by a 60 usual stop clutch, as explained in said patent, into three parts and after the operator has inspected the pulled upper and has it in correct position on the last he applies the power again and the side clamps are 65 brought into position to hold the shoe, and

the slide 124 is retracted to allow the springs 7* to press the side grippers inwardly. It is during this stage of the machine's operation that the toe lasting mechanism is operated.

For the toe lasting operation it is important that the toe end of the last occupy approximately a predetermined altitude in relation to the plane of the clamping plate 16 and, in order to adapt the mechanism to the varying longitudinal curvature or inclination of the tread faces of different lasts, this result is obtained by a toe presser 50 which is a rod having an adjustable foot and mounted for movement in the bracket 15 to engage the tread face of the toe and depress the forepart of the last. The rod is connected at its upper end with the short rear arm of the angle lever 30. The angle lever constitutes an equalizer, operating first to effect clamping of the upper and then to 75 rock slightly to effect more or less depression of the last according to the thickness of the clamped stock so that the shoe will be slightly lower if the stock is thick than if it is thin. This effect is utilized in positioning 80 the shoe properly in relation to the plate 16 for the overwiping operation to be herein-after described.

The normal angular position of the suspended angle lever 30 is determined by a 95 spring 55 that extends from the lever 28 above the pivotal connection 29 backwardly to a stationary part of the machine frame and by a detent 56 which is pivoted on the lever and held by the spring against one end 100 of a bar 818* with which machines of the illustrative type are provided for controlling the operation of the tacking mechanism. When the machine is started the second time the bar 818* is retracted in unison with the 105 bar 124 to allow the side grippers to swing inwardly and to cause the tackers to follow inwardly, although only a part of the whole distance through which they are eventually to be brought inwardly. In this movement 110 of the bars 124 and 818* the lever 28 is rocked about pivot 29, from the dotted line position to the full line position in Fig. 1 by the action of the spring 55. It will be noted that lever 28 and the rod 24 connected 115 to the clamping foot 25 constitute a toggle that is normally held substantially straight by the spring, detent, and bar 818* but which is flexed when the bar is retracted. This flexure relieves the pressure of the spring 45 120 and of the clamping foot 25 on the toe of the upper and permits it to slip more readily for the lasting operation.

The automatic lasting means comprises a 125 flexible wire lasting loop 60 which is a permanent part of the machine and is adapted to be placed around the toe of the shoe immediately below the plate 16 after the shoe has been pulled and before the machine is restarted for the second part of its cycle. 130

The loop extends backwardly along each side of the machine over guide rolls 62, Figs. 1 and 3, and has its ends fastened to brackets 64 on a slide 222 which has a cam roll 65 and is reciprocated by a cam 225 on the cam shaft, this being the same cam and slide that close the side clamps. By this construction and organization the automatic lasting means 60 is operated to draw and wipe the upper into lasted relation to the innersole around the toe, the lasting means accommodating itself automatically to the shape of the toe, and being guided in the proper wiping plane relatively to the shoe by the plate 16. The pull of the lasting loop 60 on the upper causes the clamp to give up stock under tension for drawing over the last bottom, and the pull of the loop also assists in advancing the clamping plate over the shoe bottom to the position shown in Fig. 1, such advancing movement being further assisted by the treadle spring which is sufficient of itself to effect more or less inward movement of the plate when the clamping pressure is relieved.

The machine comes to rest the second time with the parts in the position shown in Fig. 1, the upper having been worked into lasted position at the toe but not fastened. For fastening the upper the side tack carriers 10 are provided with binding cord holders, Figs. 4, 5, 6 and 7, comprising a slide 70 which has a bearing in the carrier 10 and is operated by two springs 72 to clamp and hold the cord *a* against the end of the lower plate or wiper member 74 of the tack carrier and in position under the driver holes 75 so that the tacks will pass through the cord when they are driven. The free end of the cord is held in a tapered recess formed in the edge of a rigid bar 76 and the other end is held in a similar recess in a second bar 77, the bars being connected with springs 78 to put tension on the cord. The operator applies the cord snugly by hooking one end in the bar 76 and drawing it through the adjacent holder and snugly around the toe under the lasting loop and then places it in the second holder and secures its other end in bar 77 with the spring 78 under tension. When the machine is restarted for the third and final part of its cycle the tackers complete their movement over the shoe and insert the tacks. The tackers each have a component of rearward movement in advancing to tack inserting position and this tightens the cord just before it is tacked. After the tacks are driven the machine is opened and the shoe freed with the upper pulled over and the toe lasted and bound in lasted relation to the innersole.

The improvement in methods of making shoes herein disclosed is claimed in a divisional application, Serial No. 423,631, filed 65 on November 12, 1920.

Having described my invention what I claim as new and desire to secure by Letters Patent of the United States is:—

1. A pulling-over machine having, in combination, a sole rest, a guide, a plate movable in the guide toward and from the sole rest and having its inner end recessed to embrace the toe of a shoe presented to the sole rest and permit the toe of the shoe upper to be spread over it, a clamping member movable in the guide substantially perpendicularly to the plate to clamp the upper, and yielding means to operate said member to clamp the toe of the upper on a substantially continuous line extending around the toe. 75 80

2. A pulling-over machine having, in combination, a sole rest, a clamping plate movable toward and from the rest and recessed to embrace the toe of a shoe, a clamping member to hold the toe of the upper frictionally on the plate, and means for operating the sole rest to move the last relatively to said plate to effect pulling of the upper over the toe of the last and to operate the clamping member to hold the upper until a predetermined tension is exceeded at any point and then to give up stock at such point or points while holding elsewhere. 85

3. A pulling-over machine having, in combination, a sole rest, a toe clamp comprising a plate substantially parallel with the sole rest and recessed to embrace the toe of a shoe, a clamping member shaped similarly to the plate at its inner edge, means for yieldingly operating the clamping member 100 to seize and frictionally hold the upper on a substantially continuous line around the toe of the last, means for operating the sole rest to pull the upper and locate the last with relation to the plane of the clamping plate, and means for advancing the clamping plate to lay the upper over the toe of the last. 105

4. In a pulling-over machine, the combination with side grippers, of an upper clamping plate, a co-operating clamping member, a toe presser, a pivotally suspended angle lever operatively connected with said member and presser, and means for bodily moving the angle lever to apply pressure to said member to clamp the toe of the upper against said plate and to move the presser to force the last away from the grippers and said plate. 110 115

5. In a pulling-over machine, an upper clamping plate, a co-operating clamping member, a toe presser, a single operating member connected with the presser and yieldingly connected with the clamping member, and additional means for relieving the clamping pressure without correspondingly affecting the presser. 120 125

6. In a pulling-over machine, an upper clamping plate, a co-operating clamping member, a toe presser, a single operating member connected with the presser and hav- 130

- ing a toggle connection with the clamping member, and additional means for operating the toggle to change the holding effect of the clamping member while the presser remains substantially at rest. 5
7. A pulling-over machine having, in combination, side grippers, means for holding them normally outspread for the pulling operation and permitting them to move inwardly for overdrawing the upper, toe clamping means for the upper, and connections for automatically reducing the toe clamping pressure when the grippers are allowed to move inwardly for overdrawing. 10
8. A pulling-over machine having, in combination, upper holding means comprising a toe embracing plate arranged to extend laterally of the toe from side to side, means to clamp the upper on the top face of the plate, means to effect relative movement between the last and said plate to pull the upper, and means to slide said plate lengthwise of the shoe relatively to said clamping means to draw the upper from under the clamping 20 means and wipe it over the toe of the last. 25
9. A pulling-over machine having, in combination, a sole rest, a plate arranged to extend laterally of a shoe from side to side having a recessed inner edge adapted to constitute a toe end abutment, means to clamp the upper outspread over the plate, means to operate the sole rest to force the last into the upper while said plate and clamp remain substantially stationary, means to operate 30 the plate to carry the upper over the toe of the last, and means for holding said clamping means from moving lengthwise of the last as the upper is carried inwardly over the toe. 35
10. A pulling-over machine having, in combination, a sole rest, a plate having a recessed inner edge adapted to constitute a toe end abutment, connected power operated means to clamp an upper on the plate and 40 to move the last to stretch the upper, means to advance the plate to carry the upper over the toe of the last, and means for holding the clamping means from advancing with the plate. 45
11. A pulling-over machine having, in combination, a toe embracing plate, means to clamp an upper on said plate, means for relatively moving the last and said plate and clamping means to tension the upper, a flexible loop wiper to embrace the toe adjacent to the plate, and operating means for drawing the loop wiper along said plate between the plate and the last bottom to draw and wipe the upper into lasted position over 50 the toe. 55
12. A pulling-over machine having, in combination, a sole rest, a plate having a recessed inner edge adapted to constitute a toe end abutment, means to clamp an upper 60 outspread over the plate, means to operate 65
- the sole rest to depress the last, a flexible loop wiper adapted to embrace the toe adjacent to the plate, and means for operating the wiper to work the upper into lasted position, said plate being mounted to move over the toe to hold the loop wiper in operative position. 70
13. A pulling-over machine having, in combination, a toe embracing plate, means to clamp an upper on said plate, means for relatively moving the last and said plate and clamping means to tension the upper, a flexible loop wiper to embrace the toe adjacent to the plate, means to move the plate over the toe, and means to draw the loop 80 wiper between the plate and the last bottom to wipe the upper against the lip of a welt shoe innersole. 85
14. A pulling-over machine having, in combination, a sole rest, a plate having a recessed inner edge adapted to constitute a toe end abutment, means to clamp an upper outspread over the plate, means to operate the sole rest to force the last into the upper, a flexible loop wiper adapted to be positioned adjacent to the plate, and a power operated member having a predetermined movement and connected to the wiper to draw it between the plate and the shoe bottom to pull and wipe the upper under tension over 90 the feather and against the channel lip of a welt shoe innersole on the last bottom. 95
15. In a pulling-over and toe lasting machine, means to clamp an upper around a toe of the last and to give up stock when excess tension is applied, means for relatively moving the last and the clamping means to tension the upper, a flexible loop wiper adapted to be applied around the toe, and means to operate the wiper to pull and 100 wipe the toe portion of the upper over the last bottom and to cause the clamping means to give up stock to said wiper. 105
16. In a pulling-over and toe lasting machine, means to clamp an upper around the toe of a last and to give up stock when excess tension is applied, means for relatively moving the last and the clamping means to tension the upper, a flexible loop wiper adapted to be applied around the toe, and means to operate the wiper to pull and wipe the toe portion of the upper over the last bottom and to cause the clamping means to give up stock to said wiper, said clamp being constructed and arranged to hold the 110 wiper closely upon the shoe during the overwiping operation. 115
17. In a pulling-over and toe lasting machine, means to clamp an upper around the toe of a last and to give up stock when excess tension is applied, means for relatively moving the last and the clamp to tension the upper, a flexible loop wiper adapted to be applied around the toe, and means to operate the wiper to pull and wipe the toe 120 125 130

portion of the upper over the last bottom and to cause the clamping means to give up stock to said wiper, said clamping means being constructed and arranged for movement 5 over the shoe bottom and to confine the wiper closely upon the shoe bottom during the overwiping operation.

18. In a pulling-over and toe lasting machine, a plate having a recessed edge approximately fitting the toe of a shoe, means to clamp the upper upon said plate, means to effect upper stretching, means to operate said plate to lay the upper over the last bottom in approximately lasted position, a flexible 10 loop wiper adapted to accommodate itself automatically to the contour of the toe of the particular shoe to which it is applied, and means to operate said wiper adjacent to the plate to draw the upper into fully lasted 15 position.

19. A pulling-over and toe lasting machine having, in combination, means to pull an upper, means to wipe the upper into lasted position around the toe, means mounted 20 independently of said wiping means to anchor a toe binder in position to hold the lasted upper, and power operating mechanism connected with said several means to operate them in the order recited.

20. A pulling-over and toe lasting machine having, in combination, means to pull an upper, means to wipe the upper into lasted position around the toe, means to anchor a toe binder in position to hold the 25 lasted upper, and power operating mechanism organized to pull the upper and come to rest for inspection and adjustment of the upper, to wipe the upper into lasted position and come to rest to permit presentation of

20. a toe binder, and to apply and anchor the binder and then discharge the shoe and come to rest for the presentation of another shoe.

21. In a pulling-over and toe lasting machine, means to pull over a shoe, means to 45 wipe the upper into lasted position around the toe of the shoe, and means to apply a toe binder comprising a tack carrier having a bottom plate presenting an end face adjacent to the driver passages in the carrier 50 and binder clamping means comprising a member extending across the carrier in position to clamp the binder against the end face of said plate in the path of tacks driven from the driver passages.

22. In a machine of the class described, the combination with means presenting a substantially continuous wiping edge and adapted to lay an upper over the toe of a last into approximately lasted position, of 55 a flexible loop wiper adapted to be guided along said means and to accommodate itself automatically to the contour of the toe and draw the upper into fully lasted position.

23. In a machine of the class described, 60 the combination with means presenting a

substantially continuous wiping edge adapted to lay an upper over the toe of a last and into approximately lasted position over a welt shoe innersole, and a device for frictionally clamping the margin of the upper 70 against said means, of a flexible wire loop wiper adapted to accommodate itself to the contour of the toe and to draw stock from said clamping device and wipe the upper into fully lasted relation to the lip of the 75 innersole.

24. A machine of the class described having, in combination, means for clamping the margin of an upper substantially continuously round the end of a shoe form from one side of the form to the other, means for effecting relative movement of said clamping means and the form to pull the upper, a flexible wiper member adapted to extend round the end of the tensioned upper, and 80 means for operating said flexible member to wipe the upper inwardly over the bottom face of the form, said clamping means being constructed to permit the margin of the upper to yield inwardly in response to the 85 pull of said member.

25. A machine of the class described having, in combination, means for clamping the margin of an upper in outspread condition round the end of a shoe form, means for effecting relative movement of said clamping means and the form to pull the upper, a flexible wiper member adapted to extend round the end of the tensioned upper, and 90 means for pulling said member rearwardly to wipe the upper over the bottom face of the form while the margin of the upper is retained under the control of said clamping means.

26. A machine of the class described having, in combination, means for clamping the margin of an upper round the end of a shoe form, power operated means for effecting relative movement of said clamping means and the form to pull the upper, a flexible 100 wiper member adapted to extend round the end of the tensioned upper, and means automatically operative in time relation to other parts of the machine to pull said member rearwardly and wipe the upper over the bottom face of the form.

27. A machine of the class described having, in combination, means for clamping the margin of an upper in outspread condition round the end of a shoe form, means for effecting relative movement of said clamping means and the form to pull the upper, a flexible wiper member adapted to extend round the end of the tensioned upper, and operating means connected to portions of 110 said member at the opposite sides of the shoe to pull it rearwardly and wipe the upper into lasted relation to the lip of an insole on the form while the margin of the upper is 115 retained in control of said clamping means.

28. A machine of the class described having, in combination, a pair of clamp members co-operating to clamp the margin of an upper in outspread condition round the end 5 of a shoe form, means for effecting relative movement of said members and the form to pull the upper, and means for working the upper into lasted position over the form while the margin is held by said members, 10 one of said members being movable relatively to the other along the clamping plane in response to the pull of the upper as it is worked into lasted position.
29. A machine of the class described having, in combination, a pair of clamp members co-operating to clamp the margin of an upper in outspread condition round the end of a shoe form, means for effecting relative movement of said members and the 15 form to pull the upper, a flexible wiper member adapted to extend round the end of the tensioned upper, and means for pulling said member rearwardly to wipe the upper inwardly over the bottom of the form, one of 20 said clamp members being movable relatively to the other lengthwise of the form in response to the pull of said wiper member.
30. A machine of the class described having, in combination, means for clamping the margin of an upper in outspread condition round the end of a shoe form, means for effecting relative movement of said clamping means and the form to pull the upper, a 25 flexible member adapted to extend round the end of the tensioned upper, and means for pulling said flexible member rearwardly to draw the upper into conformity to the contour of the form, said clamping means comprising a member movable rearwardly in 30 response to the pull of said flexible member and arranged to guide said flexible member in its operative movement.
31. A machine of the class described having, in combination, means for clamping the margin of an upper in outspread condition round the end of a shoe form, means for effecting relative movement of said clamping means and the form to pull the upper, a 35 flexible wiper member adapted to extend round the end of the tensioned upper, and means for operating said flexible member to wipe the upper inwardly over the bottom of the form, said clamping means comprising a 40 plate mounted for movement over the bottom of the form in wiping engagement with the upper and arranged to guide said flexible member in its operative movement.
32. A machine of the class described having, in combination, means for clamping the margin of an upper round the end of a shoe form, means for effecting relative movement of said clamping means and the form to pull the upper while permitting the margin of 45 the upper to slip at points of excessive tension, means for working the upper into conformity to the contour of the form while the margin is under control of said clamping means, and mechanism for operating said clamping means partially to release the 50 clamping pressure and permit the margin of the upper to slip more freely in response to the pull as it is worked inwardly about the form.
33. A machine of the class described having, in combination, means for clamping the margin of an upper round the end of a shoe form, power operated means for effecting relative movement of said clamping means and the form to pull the upper, means for 55 working the upper inwardly about the form while the margin is held by the clamping means, and mechanism automatically operative at a predetermined time in the cycle of the machine partially to release the clamping pressure to permit the margin of the upper to slip as it is worked inwardly.
34. A machine of the class described having, in combination, means for clamping the margin of an upper round the end of a shoe form, means for effecting relative movement of said clamping means and the form to pull the upper, a flexible member adapted to extend round the end of the tensioned upper, means for pulling said member rearwardly to draw the upper into conformity to the 60 contour of the form, and means automatically operative at a predetermined time in the cycle of the machine to relax the pressure of said clamping means on the margin of the upper and permit the margin to slip in response to the pull of said flexible member.
35. A machine of the class described having, in combination, a pair of clamp members arranged to clamp the margin of an upper in outspread condition round the end of a shoe form, operating means for moving one of said members relatively to the other to clamping position including a toggle arranged to be maintained in substantially straight condition for clamping the upper, means for effecting relative movement of the clamping means and the form to pull the upper, means for working the upper into 65 lasted position, and means for flexing said toggle to relieve the pressure of the clamping means on the margin of the upper and permit the margin to slip in response to the pull of the lasting means.
36. In a machine of the class described, means for clamping the margin of an upper round the end of a shoe form, a tread rest, and operating mechanism for said clamping means and tread rest to cause the upper to 70 be clamped by the clamping means and the form to be moved by the tread rest to pull the upper, said operating mechanism being constructed to effect automatically a variation in the extent of the movement of the 75 upper.

tread rest proportional to the thickness of the clamped upper stock.

37. A machine of the class described having, in combination, means for clamping the margin of an upper round the end of a shoe form, grippers for engaging the upper at opposite sides of the form, means for moving the form relatively to said clamping means and grippers to pull the upper, means for maintaining said clamping means substantially stationary during the upper pulling operation, means for moving said grippers inwardly to overdraw the upper, and means for working the margin of the upper into lasted position round the end of the form.

38. A machine of the class described having, in combination, means for clamping the margin of an upper in outspread condition round the end of a shoe form, grippers for engaging the upper at opposite sides of the form, means for effecting relative movement of the form and said clamping means and grippers to pull the upper, means to cause said grippers to overdraw the upper, a flexible wiper member arranged to extend round the end of the upper, and means for pulling said flexible member rearwardly to wipe the upper into lasted position round the end of the form.

39. In a machine of the class described, a flexible member adapted to extend round the end of a shoe form, means for pulling said member lengthwise of the form to draw an upper to the contour of the form, and means for applying a binder round the end of the form and fastening it to hold the upper in its shaped condition.

40. In a machine of the class described, a flexible member adapted to extend round the end of a shoe form, power operated means for pulling said member lengthwise of the form to draw an upper to the contour of the form and for then holding it to permit a binder to be placed round the upper, and means automatically operative upon a subsequent starting of the machine to fasten the binder to the upper.

41. In a machine of the class described, the combination with shoe positioning means, of a flexible wiper member adapted to extend round the end of the shoe, means for pulling said member lengthwise of the shoe to wipe the upper into lasted position, and means for applying and fastening a lasting binder to retain the upper in lasted position.

42. In a machine of the class described, the combination with shoe positioning means, of a flexible wiper member adapted to extend round the end of the shoe, power operated means for pulling said member rearwardly to wipe the upper into lasted relation to a welt shoe insole, and power operated means for applying a binder in

holding relation to the upper and for fastening it in place.

43. In a machine of the class described, the combination with shoe positioning means, of a flexible wiper member adapted to extend round the end of the shoe, power operated means for pulling said member rearwardly to wipe the upper into lasted position and for then maintaining it in position to hold the upper in lasted condition with the machine at rest to permit a binder to be placed round the end of the shoe, and means automatically operative when the machine is again started to fasten said binder to the shoe.

44. A machine of the class described having, in combination, means for clamping the margin of an upper round the end of a shoe form, means for effecting relative movement of said clamping means and the form to pull the upper, a flexible member adapted to extend round the end of the tensioned upper, means for operating said member to draw the upper into conformity to the contour of the form, and means for fastening a binder in position to hold the upper to the contour of the form before the pressure of said flexible member on the upper is released.

45. A machine of the class described having, in combination, means for clamping the margin of an upper round the end of a shoe form, a flexible member adapted to extend round the end of the upper, power operated means for effecting relative movement of said clamping means and the form to pull the upper and for operating said flexible member to draw the upper to the contour of the form, and power operated means for fastening a binder to the upper to hold it in conformity to the contour of the form.

46. A machine of the class described having, in combination, a flexible wiper adapted to extend round the toe end of a last, means for operating said wiper to wipe the margin of an upper inwardly round the toe over the feather and against the lip or shoulder of a sole on the bottom of the last, and means for clamping the margin of the upper on a substantially continuous line round the toe and for maintaining the upper in an unwrinkled condition round the toe during the operation of said flexible wiper.

47. A machine of the class described having, in combination, a flexible wiper adapted to extend round the toe end of a last, means for operating said wiper to wipe the margin of an upper inwardly round the toe over the feather and against the lip or shoulder of a sole on the bottom of the last, and means for clamping the margin of the upper yieldingly on a substantially continuous line round the toe to hold the upper under tension against a predetermined pull of said flexible wiper and to give up stock from the clamped margin at any point where said tension is exceeded.

48. A machine of the class described having, in combination, means for clamping the margin of an upper round the toe end of a last, mechanism for effecting relative movement of said clamping means and the last to pull the upper heightwise of the last, a flexible wiper adapted to extend round the toe end of the last, means for operating said flexible wiper to wipe the upper inwardly over the feather and against the lip or shoulder of a sole on the bottom of the last while the margin of the upper is under the control of said clamping means, and means for operating said clamping means partially to release the pressure on the margin of the upper to permit the margin to slip in response to the pull of said flexible wiper.
49. A machine of the class described having, in combination, means for pulling an upper over a shoe form and for working the upper inwardly about the form comprising a clamping device constructed to hold the marginal portion of the upper under yielding pressure while permitting it to slip as the upper is pulled over the form and as it is worked inwardly about the form, and means for operating said clamping device after the upper has been pulled over the form to relax the clamping pressure and permit the margin to slip more freely as it is worked inwardly about the form.
50. A machine of the class described having, in combination, power operated means for pulling an upper over a shoe form and for working the upper inwardly about the form comprising a clamping device constructed to control the marginal portion of the upper as it is pulled over the form and as it is worked inwardly, and mechanism automatically operative at a predetermined time in the cycle of the machine to relax the clamping pressure on the margin of the upper to permit the upper to be worked inwardly about the form with the margin held under a reduced pressure.
51. A machine of the class described having, in combination, power operated means for pulling an upper over a shoe form and for working the marginal portion of the upper inwardly over the bottom of the form comprising a clamping device constructed to hold the marginal portion of the upper under yielding pressure and to permit it to slip in both the pulling and the overworking operations, and mechanism automatically operative at a predetermined time in the cycle of the machine to relax the clamping pressure and permit the margin of the upper to slip more freely in the overworking operation than in the upper pulling operation.
52. A machine of the class described having, in combination, power operated means organized to pull an upper over a last and to come automatically to a stop with the upper held under tension, a flexible wiper arranged to extend about the toe portion of the last, and means automatically operative upon a subsequent starting of the machine to draw said wiper about the toe of the last for conforming the upper to the contour of the last.

In testimony whereof I have signed my name to this specification.

ARTHUR BATES.
